No. 36,964.

Patented June 14, 1904.

UNITED STATES PATENT OFFICE.

JEAN G. A. FORTIER, OF ST. PAUL, MINNESOTA.

DESIGN FOR A FRONT FOR PLAYING-CARDS.

SPECIFICATION forming part of Design No. 36,964, dated June 14, 1904.

Application filed May 2, 1904. Serial No. 206,088. Term of patent 7 years.

To all whom it may concern:

Be it known that I, JEAN G. A. FORTIER, a citizen of the United States, residing at St. Paul, in the county of Ramsey and State of Minnesota, have invented a new, original, and ornamental Design for the Front of Playing-Cards, of which the following is a specification, reference being had to the accompanying drawing, forming part thereof.

o The figure is a view of a front of a playing-card, showing my new design.

What I claim as new, and desire to secure by Letters Patent, is--

The ornamental design for the front of a playing-card, as shown.

JEAN G. A. FORTIER.
